UNITED STATES PATENT OFFICE.

FREMONT J. CLEAVER, OF CARNEGIE BOROUGH, PENNSYLVANIA, ASSIGNOR OF ONE-THIRD TO SAMUEL L. H. MORRIS AND ONE-THIRD TO HERBERT W. HODGDON, BOTH OF PITTSBURGH, PENNSYLVANIA.

MULTIPLE REFILLABLE FUSE.

1,226,780.

Specification of Letters Patent. Patented May 22, 1917.

Application filed October 5, 1915. Serial No. 54,281.

To all whom it may concern:

Be it known that I, FREMONT J. CLEAVER, a citizen of the United States, and residing in Carnegie Borough, in the county of Allegheny and State of Pennsylvania, have invented or discovered new and useful Improvements in Multiple Refillable Fuses, of which the following is a specification.

My invention consists of a multiple, refillable electric fuse.

My improved fuse is characterized by a plurality of fusible elements which, without disassembling the fuse, may singly or one at a time be placed in circuit until all of the fusible elements are fused. Said elements are preferably arranged in the form of a cartridge or filler, so that, when all of the fusible elements in the cartridge have been blown, the used cartridge may be removed from the fuse casing and a fresh cartridge substituted.

Other novel features of construction and arrangement of parts will appear from the following description.

In the accompanying drawings, Figure 1 is a longitudinal section of one of my improved fuses; Fig. 2 is a section taken along the line II-II in Fig. 1; Fig. 3 is a face view of one of the insulating washers; Fig. 4 is a section along the line IV-IV in Fig. 1; Fig. 5 is a section along the line V-V in Fig. 1; Fig. 6 is a longitudinal section of a modification; Fig. 7 is a section along the line VII-VII in Fig. 6; Fig. 8 is a side elevation of the cartridge removed from the fuse casing; Fig. 9 is a longitudinal section of a second modification; Fig. 10 is an end view of the same looking toward the left in Fig. 9, and Fig. 11 is an isometric view of the plug used in connection with the fuse shown in Fig. 9.

The following is a detailed description of the drawings, reference being first had to Figs. 1, 2, 3, 4 and 5.

A is a circular plate of brass or other conductive material, provided on one face with an annular series of sockets 1 in which are soldered or otherwise secured the butts of the brass studs or projections 2. To the outer ends of said studs are soldered or otherwise permanently attached the fusible elements B, shown as wires, one of said elements being attached to each stud. Said fusible elements are provided with a reduced

intermediate portion or zone b to localize the fusion when the same takes place.

C is a circular washer of insulating material, such as fiber, of somewhat less diameter than the plate A and provided with perforations 3 through which the studs 2 extend. D is a similar insulating washer of still less diameter provided with tapered perforations 4 which cover the unions between the studs and the fusible members and through which said members protrude, as shown.

E represents longitudinally slit tubes of asbestos or other insulating material, slipped over the elements B and having their slits or lines of severance turned inwardly, as shown in Fig. 2. Normally said slits are tightly closed, thus holding the elements in air-tight tubes, but when the element fuses or blows, said slits open to exhaust the arc and permit the gases to escape. The other ends of said elements protrude from said tubes through perforations 5 in a second fiber washer F which is also provided with a central aperture 6.

The washer F is of the same diameter as the washer D.

G is a circular plug of insulating material, of the same diameter as the washer C, provided with a central aperture 6a in alignment with the said aperture 6 in the washer F. The plug G is provided with an annular series of perforations which register with the ends of the elements B. 7 are brass nipples mounted in said perforations. Said nipples may be provided with circumferential flanges on their inner ends and are threaded to receive the nuts 8 on their outer ends, whereby said nipples are firmly anchored in the perforations of said plug. The inner ends of said nipples are provided with sockets in which the ends of the elements B are secured in any convenient manner, as by solder. The outer ends of said nipples are interiorly threaded for a purpose to be described.

H is a cylindrical wrapping or envelop of insulating paper or fabric whose edges are overlapped and pasted together and whose ends encircle the washers D and F and abut against the washer C and the plug G. The space within the envelop between and about the tubes E is filled with an arc-absorbing material, I, such as chemi-

callously treated asbestos particles, which may be filled in through the apertures 6 and 6^a, which apertures also serve to permit the escape of the gases generated by the fusion 5 of one of the elements B.

The parts above described are thus assembled together to form a cartridge, shown in Fig. 8, which is inserted in an outer casting which I will now proceed to describe.

10 J is a cylinder of insulating material, such as fiber, of proper internal diameter to slip down over the cartridge and abut against the face of the brass plate A, as shown in Fig. 1, the cylinder being of sufficient length to protrude beyond the plug G slightly, as shown.

K is a brass cap provided with an annular flange which fits over the edge of the brass plate A and over the end of the cylinder J. Screws 9 extend through holes in the head of cap K and engage threaded holes in the brass plate A whereby said cap and said plate are drawn together in close electrical contact. Said cap is preferably provided with the usual knife-blade contact 10. Screws 11 extend through holes in the flange of the cap K and the cylinder J into threaded holes in the perimeter of washer C.

36 L is the cap for the other end of the fuse provided with an annular flange which fits over the other end of cylinder J but is held out of contact with the plug G by the length of said cylinder extending beyond said plug. Thus there is no direct contact between the cap L and the nipples 7. Screws 11^a extend through holes in the flange of the cap L and cylinder J into threaded holes in the perimeter of the plug

40 G, said threaded holes being positioned to properly place the cap. The cap L is provided with an annular series of holes 12, each in alignment with one of the nipples 7 of the plug G. Said holes 12 are threaded, 45 and 13 is a brass screw which may be screwed into any one of the holes 12 and into the threaded bore of the nipple 7 which is in alignment with the particular hole 12. It is evident that electrical connection is 50 thus completed through one of the fusible elements B.

14 is the usual knife-blade contact of the cap L.

It is evident that by changing the screw 55 13 from one hole 12 to another, different elements B are connected between the caps K and L, so that when the element B which is so connected is fused or blows, the screw 13 is changed to another position, thus putting each of the elements into circuit until they have all become fused, when the cartridge is removed and one full of intact fuses is substituted. The removal of the cartridge is readily effected by loosening 65 the screws, 9, 11 and 11^a and also taking

out the screw 13. Then the caps K and L and the cylinder J are removed and placed upon a fresh cartridge.

The cartridges may be assembled at the factory and sold to consumers to be installed by the latter when required.

When a fusible element B blows, the arc will escape from the tube E and be absorbed by the filling I and the gases generated by said fusion will escape through the apertures 6 and 6^a and the unoccupied screw holes 12 in the cap L to atmosphere. The slitting of the tube E permits the escape of the arcs and gases without rupture and without interfering with inclosure of the unblown fusible members.

In Figs. 6 and 7 I show the fusible members in the form of flat blades B', the studs 2 being of similar cross-section and the washers C, D and F being provided with radially placed slots instead of round holes. Said fusible members are provided with envelopes E' of rectangular cross-section instead of the round tubes E of Fig. 1, said envelopes E' having their inner walls slit, as shown in Fig. 7. The ends of elements B' are secured in slots in the ends of the nipples 7 of the plug G.

In Figs. 9, 10 and 11 I show modified means for completing the circuit through the fusible elements instead of the contact screw shown in the prior views. The ends of the elements B are here attached to the inner ends of the contact posts 15 which are fixed in the plug M of insulating material. The ends of said posts 15 protrude from the outer face of said plug, forming an annular series of spaced apart contact points.

The end of cap L' is cut away at the center to leave an annular flange 16 which fits down into the annular shoulder 17 on the end of the plug. 18 is an annular raised lip on said flange of cap L' concentric with said plug.

A contact arm 19 is pivoted on the insulated headed pin 20 mounted at the axis of plug M. Said arm is rotatable into any position, thus enabling connection to be completed between the lip 18 and any one of the contact posts 15. Thus any one of the fusible members may be connected to the caps, and when said member blows, the contact arm 19 may be shifted to connect up another fusible member. A spring 21 on the pin 20 insures good contact on the part of arm 19. 22 are perforations through the plug M to permit the escape of the gases of fusion.

The form of fuse illustrated in Figs. 9, 10 and 11 is particularly intended for use in connection with currents of relative low amperage, and the caps are shown adapted to be mounted in the usual spring clamp contact members.

From the foregoing, it is evident that my improved fuse, in the several forms illustrated, is attended by many and important advantages. Thus the fuse need not be renewed after each blowing, but the movable contact need only be switched to restore the circuit. No injury is received by the fuse from the blowing of its fusible members, as the split tubes protect the various fusible elements from injury, the arcs are absorbed by the filling and the gases escape freely from the fuse.

What I desire to claim is:

1. In a multiple, refillable fuse, the combination of a pair of end members of conductive material adapted to be electrically connected to opposing line terminals, a plurality of fusible members having their one ends fixed to one of said end members and extending toward the second end member, an insulating member adjacent to the second end member, a plurality of socket members of conductive material carried by said insulating member and insulated from each other, the end of each of said fusible members being held in one of said socket members, and a movable conductive element adapted to establish electrical connection between any one of said socket members and the second end member, for the purpose described.

2. In a multiple, refillable fuse, the combination of a pair of end members of conductive material adapted to be electrically connected to opposing line terminals, a plurality of fusible members having their one ends fixed to one of said end members and extending toward the second end member, an insulating member adjacent to the second end member, a plurality of socket members of conductive material carried by said insulating member and insulated from each other, the end of each of said fusible members being held in one of said socket members, a movable conductive element adapted to establish electrical connection between any one of said socket members and the second end member, and an insulating cylinder interposed between said end members to inclose said fusible members, for the purpose described.

3. In a multiple, refillable fuse, the combination of a pair of end members of conductive material adapted to be connected to opposing line terminals, a plurality of fusible members having their one ends fixed to one of said end members and extending toward the second end member, an insulating member adjacent to the second end member, a plurality of socket members of conductive material carried by said insulating member and insulated from each other, the end of each of said fusible members being held in one of said socket members, and an insulating cylinder interposed between said end members to inclose said fusible members, for the purpose described.

ble members having their one ends fixed to one of said end members and extending toward the second end member, an insulating member adjacent to the second end member, a plurality of socket members of conductive material carried by said insulating member and insulated from each other, the end of each of said fusible members being held in one of said socket members and said socket members being provided with outer threaded bores, and a conductive screw member adapted to be inserted through the second end member and screwed into the bore of any one of said socket members, for the purpose described.

4. In a multiple, refillable fuse, the combination of a pair of end members of conductive material adapted to be connected to opposing line terminals, a plurality of fusible members having their one ends fixed to one of said end members and extending toward the second end member, an insulating member adjacent to the second end member, a plurality of socket members of conductive material carried by said insulating member and insulated from each other, the end of each of said fusible members being held in one of said socket members and said socket members being provided with outer threaded bores, a conductive screw member adapted to be inserted through the second end members and screwed into the bore of any one of said socket members, and an insulating cylinder interposed between said end members to inclose said fusible members, for the purpose described.

5. In a multiple, refillable fuse, the combination of a pair of conductive end members adapted to be electrically connected to opposing line terminals, a plurality of fusible members individually connected electrically to one of said end members, means for electrically connecting said fusible members individually to the second end member, an individual insulating envelop for each of said fusible members split along one of its sides from end to end to open for the escape of the gas of fusion, and an insulating shell interposed between said end members and inclosing said fusible members and their envelops for the purpose described.

Signed at Pittsburgh, Penna., this 4th day of October, 1915.

FREMONT J. CLEAVER.
